ARTIFICIAL LIMB

Nicholas Malloy-Brehunoff, Bridgeport, Conn.

Application March 22, 1935, Serial No. 12,346

8 Claims.

(Cl. 3-2)

This invention relates to new and useful improvements in artificial limbs and has for an object to provide an artificial limb including certain adjustable connections whereby the limb may be adjusted to give the greatest comfort to the wearer.

It is also an object to provide an artificial limb that will permit walking and using of the limb to better effect than such limbs now available.

10 The invention also includes improvements in the harness for attaching or securing an artificial limb to a wearer, improved connections at the knee joints of artificial limbs, and improved foot and calf connections for artificial limbs.

15 Other objects and advantages will become apparent from a consideration of the following detailed description taken in connection with the accompanying drawings wherein satisfactory embodiments of the invention are shown. However, it will be understood that the invention is not limited to the details disclosed but includes all such variations and modifications as fall within the spirit of the invention and the scope of the appended claims.

25 In the drawings:

Fig. 1 is a front elevational view of an artificial limb adapted to be used when the wearer's leg has been amputated above the knee joint, parts being broken away in the view to show features 30 of construction;

Fig. 2 is a side elevational view of the limb of Fig. 1 with parts broken away;

Fig. 3 is an enlarged detail view showing the construction at the knee joint and particularly 35 showing a locking means employed;

Fig. 3a is a detail side view of a catch for rendering the lock ineffective;

Fig. 3b is a top plan view thereof;

Fig. 4 is a top plan view of the foot of Figs. 40 1 and 2;

Fig. 5 is a front elevational view showing the harness employed for securing either the limb of Figs. 1 and 2 to the wearer; and

Fig. 6 is a rear elevational view showing the 45 harness in use.

Referring in detail to the drawings, and at first particularly to Figs. 1 through 4, the artificial limb of such figures as shown includes a thigh portion 10, a calf 11, and a foot 12. This limb 50 is for use where the leg of the wearer has been amputated above the knee joint and the thigh 10 is a socket-like construction including a metal shell 13, a felt pad 14 against the inner side of said shell and a leather inner lining 15. Joint 55 holders and adjustment plates 16 are riveted to

the opposite sides of the thigh 10 as at 17 and such plates extend toward the lower end of the thigh and adjacent their upper ends are provided with a set of vertically spaced tapped openings 18 and toward its lower end each plate is provided with a tapped opening 19.

The knee joint between the thigh 10 and cap 11 is generally designated 20 and includes upper parts 21 and lower parts 22. At their upper ends the parts 21 are provided with head-like enlargements 23 whereby the parts are somewhat T-shaped and such head-like portions are each provided with a series of horizontally spaced openings 24. In spaced relation to the heads 23 the parts 21 are each provided with a series of vertically spaced openings or perforations 25. Bolts 26 and 27 are passed through selected ones of the upper and lower sets of openings 24 and 25 respectively to secure the upper knee joint parts 21 to the mounting and adjustment plates 16 and through such plates to the thigh 10. The bolt 26 is passed through a selected one of the openings 24 in the part 21 and is threaded into the selected opening 18 in the plate 16.

When the bolt 26 is in position it determines 25 which of the openings 25 in the part 21 the bolt 27 is to be passed through in order to thread into the opening 18 of the plate 16. The bolt 27 may be first screwed into place after which the thigh 10 may be adjusted and then the bolt 26 screwed into place. By the dotted line positions of the thigh 10 in Fig. 2 it is shown that the thigh may have various positions of adjustment relative to the upper parts 21 of the knee joint. The thigh 30 may be adjusted vertically and it may also be tilted more or less so as to be given that relation to the calf 11 which is most comfortable to the wearer.

The lower knee joint parts 22 are disposed 40 against the inner surfaces of the calf 11 at diametrically opposite sides thereof and are secured in place by screws 28. Such parts extend above the upper end of the calf and their upper end portions 29 are bifurcated. The upper parts 21 of the knee joint extend below the lower end 45 of the thigh 10 and are received in the bifurcated portions 29 of the part 22 and such parts 21 and 22 are hingedly connected by pin bushings 30 into which are threaded the securing screw 31. With the described construction it will be apparent 50 that the thigh 10 and calf 11 are hingedly connected and that the thigh may be adjusted relative to the calf so that the thigh will occupy that position which will give the most comfort to the wearer, and also the lower part of the leg 55

may be swung backwardly when the wearer sits down, or at any time desired.

At the front side of the artificial limb the space between the lower end of the thigh 10 and the upper end of the calf 11 is closed by a knee cap plate 32. Screws 33 secure the upper end portion of the plate 32 against the inner surface of the lower end portion of the thigh and such plate extends for a substantial distance into the calf 11. This knee cap plate is formed of flexible spring metal as for example bronze and when the artificial limb is bent the lower portion of the plate slides along the inner surface of the calf 11 and the plate bends and maintains the space between the front portions of the thigh and calf closed, flexing and functioning in the manner of a natural knee cap.

A locking means generally designated 34 is provided to prevent free pivotal movement between the thigh 10 and the calf 11 when the wearer is walking on the artificial limb. A substantially semi-circular member or plate 35 has its end portions secured to the upper parts 21 of the knee joint 20 as by rivets 36 and at the inner side of said plate are a pair of ears 37 secured by rivets 38 and extending inwardly and downwardly with respect to the plate. An eye bolt 39 has its head disposed between the ears 37 and a bushing 40 passes through the ears and eye bolt 39 and pivotally mounts the eye bolt.

On the lower end of the eye bolt 39 there is threaded a push rod 41 comprising a tubular member into which the eye bolt 39 threads and in transverse section the exterior of this push rod is non-circular preferably being square. A counter or lock nut 42 is threaded onto the eye-bolt 39. The lower end of the push rod 41 passes through an opening in a bushing 43 which bushing is threaded into the upper end of a cylinder 44. Below the bushing 43 the push rod is provided with an enlargement or a head 45 of such diameter as to be incapable of passing through the opening in the bushing 43 and the opening in such bushing is shaped to conform to the exterior shape of the push rod so that the latter has no turning movement in the bushing.

Within the cylinder 44 and bearing at one end against the head 45 of the push rod is a spring 46 constantly exerting an effort against the lower end of the push rod. Obviously, the push rod may be adjusted on the eyebolt 39, and the bushing 43, owing to its threaded connection to its cylinder 44, is adapted to adjust the tension of the spring 46 since the bushing may be threaded more or less into the cylinder as desired by turning of rod 41 by a suitable wrench, and it may then be locked by nut 42. A small bracket 47 is secured against the inner surface of the rear wall of the calf 11 as by screws 48. When the artificial limb is being used the lower end of the cylinder 44 bears against the horizontal arm of the bracket 47 as shown in Figs. 1 and 2 and the spring 46 provides the necessary cushion between the calf and thigh and produces the oscillation of the thigh.

About the lower end portion of the cylinder 44 is an unlocking or releasing ring 49 prevented from sliding off the cylinder by a protecting or stop ring 50. Connected with the unlocking ring 49 is a cord 51 adapted to be pulled or drawn to move the lower end of the cylinder 44 off the bracket 47 so that the artificial limb may pivot at the knee joint when the wearer is sitting. It may also be released by pressing inwardly with a finger of the wearer's hand against the back of

member 44. At such times the cylinder will be positioned as shown by the dotted line in Fig. 2. To again straighten the leg the wearer may shake or snap it to have the calf 11 assume a straight position with respect to the thigh 10, and when this is done the lower end of the cylinder is moved back onto the horizontal arm of the bracket 47 by means of a spring 52 which normally acts to maintain the cylinder in the last described position.

Spring 52 as shown is formed from a single length of wire bent intermediate its ends to provide a pair of arms and a connecting portion 53 and the spring is arranged with this connecting portion bearing against the forward side of the cylinder 44. Intermediate their ends the arms of the spring are bent to provide coils 54 passed over the extending ends of the bushing 40 and then the free ends 55 of the arms of the spring bear against the ears 37. A bolt having a relatively large head 56 is passed through the bushing 40 and a relatively large nut 57 is threaded onto the bolt and the head 56 and nut 57 provide means to prevent the coils 54 of the spring from moving off the ends of the bushing. With this arrangement it will be apparent that the spring is constantly tending to move the cylinder 44 in a direction to push the cylinder against the inner surface of the rear wall of the calf 11.

The pull cord 51 is carried outwardly against the under side of a pulley 58 mounted between a pair of plates 59 which plates are supported by tubular members 60 extending across the calf 11 in vertical spaced relation to one another and secured in position by the intermediate pairs of screws 28 used in securing the lower parts 22 of the knee joint to the calf. On passing under the pulley 58 the pull cord 51 is carried upwardly as shown in Fig. 2 and passes out of the artificial leg through an opening 61 in the lower portion of the thigh 10. The manner in which the outer or upper end of the cord 51 is secured will later be set forth.

If desired a catch may be provided as shown in Figs. 3a and 3b whereby this lock may be prevented from moving to locking position. For example, when driving a car it would be undesirable to have the leg lock in straightened position after pushing downwardly on the brake pedal as it might be necessary to unlock the joint before the brake could be released. This latch may take various forms but as shown comprises a catch member 47a pivoted to the bracket 47 at 47b. A spring 47c is secured to the catch at 47d and to the shell 11 at 47e. This catch may be shifted to a position over the bracket 47a as shown in full lines when it will hold the lock 44 off the bracket as shown so it can not lock. If the catch is swung to one side as indicated in dotted lines it will not prevent member 44 going over the top of the bracket and locking as indicated above. In these movements the spring 47c passes over the pivot 47b and so holds the catch in either position. The catch may be provided with a finger piece 47f or an opening 47g which may be engaged by a finger to move it to either position.

Calf 11 and foot 12 are connected by an ankle joint generally designated 52 and which joint comprises upper parts 63 secured against the inner sides of the lower portion of the calf 11 as by rivets 64 and lower parts 65 disposed in channels 66 and secured against opposite sides of a base 67 of the foot as by bolts 68 passing transversely through such base. The lower ends of

the parts 63 are received in the bifurcated upper end portions of the parts 65 and bushing pins 70 are passed through the overlapping end portions and screws 71 are passed through the joints 5 to secure the parts. From this it will be apparent that the calf 11 and foot 12 are pivotally connected.

In addition to the base 67, which is preferably a metal casting, the foot 12 includes a felt toe 72 and beneath the base and the toe there is arranged the shock absorbing sponge rubber pad 73. Screws 74 are preferably used for securing the toe 72 to the base 67. At the under side of the pad 73 there is arranged a leather sole 75 and it will be understood that a regular shoe may be worn on the foot. Preferably the foot 12 includes a leather casing or cover 76. A plate or closure 77 is arranged in the lower end of the calf 11 and is preferably welded therein as at 78. Arranged in the base 67 are a pair of similar springs 79 and 80 and the spring 79 is arranged forwardly of the pivot of the ankle joint while the spring 80 is arranged rearwardly of said pivot.

25 The upper ends of these springs are secured to the plate 77 as at 81 and the lower end of the spring 79 is engaged by an adjustable screw 82 while the lower end of the spring 80 is engaged by a similar screw 83, the said screws being 30 threaded through the bottom wall of the base 67. The cushioning pad 73 and the leather sole 75 are provided with openings 84 giving access to the lower ends of the screws 82 and 83 whereby said screws may be adjusted. By adjusting 35 said screws to decrease or increase the tension of the springs 79 and 80 the position of the toe of the foot relative to the calf 11 may be carefully regulated. The springs may be independently adjusted since there is a separate regulating screw for each spring.

A harness later to be described is provided for securing the artificial limb to the wearer and the thigh portion 10 carries the means by which such harness connects with the limb. This means includes pulleys 85 and 86 located at the outer sides of the thigh 10 and of which one is carried by each of the upper parts 21 of the knee joint. The pulleys are secured in place or clamped against the parts 21 by plates 87 secured to the parts by screws 88 passing through the plates and threaded into the parts 21. Spacer bushings may be provided about the screws if desired and an intermediate screw 89a mounts the pulley. When the described leg is in use a 55 strong cord of leather or the like is passed under the pulleys 85 and 86 and attached to a harness on the wearer so as to secure the artificial leg onto the stump of the wearer's leg.

To mount or secure in place the artificial leg 60 a harness such as shown in Figs. 5 and 6 is employed. This harness includes a relatively wide preferably leather belt or corset 134 secured about the waist of the wearer as by a plurality of straps and buckles 135. Suspender means comprising 65 straps 136 are secured to the front portions of the belt as at 137 and at the back of the wearer the straps may be crossed as at 138 and have their ends sewed or otherwise secured to the belt as at 139. Adjacent its lower edge the belt is provided 70 with spaced pairs of perforations 140.

By means of an elastic tape or strap 141 a support 142 carrying a pulley 143 is attached to the belt 134. Pairs of hooks 144 may be used for attaching the ends of the elastic 141 to the 75 belt and such hooks are passed through conven-

ient pairs of the openings 140 in the belt whereby the pulley 143 will be mounted to give the most convenience and comfort to the wearer. A strong cord of leather or the like 145 is passed over the pulley 143 and then down under the pulleys 85 and 86 and the ends of the cord are brought up at the front of the wearer and connected with a buckle 146 secured to the belt 134 as by a tab 147. This same arrangement is as above suggested used for securing either form of 10 the artificial limb to the body of the wearer. The elastic 141 serves to keep the cord 145 taut and to hold the thigh portion of the artificial limb always against the stump of the wearer's leg but permits free movements of the wearer's body 15 and leg in all directions whether he is standing or sitting.

When the leg of Figs. 1 and 2 is being used it is preferred that the pull cord 51 of the locking means be connected with the supporting 20 buckle 46. With such an arrangement a user may by raising his shoulder exert a pull on the cord 51 so as to draw the lower end of the cylinder 44 off the bracket 47 and thus unlock the knee joint. Attention is directed to the fact that 25 the artificial limb of the present invention is entirely free of wood, being made of metal, felt and leather. It is preferred that a light strong metal such as an aluminum alloy be used in the construction of the metal parts.

Having thus set forth the nature of my invention, what I claim is:

1. In an artificial leg construction, a thigh section, a calf section, a knee joint connecting said sections comprising a pair of upper parts 30 extending at the sides of the thigh section, a pair of lower parts secured to the calf section and pivoted to the said upper parts to permit relative pivotal movement between the thigh and calf sections during normal operation, and adjustable means connecting the thigh section to said upper parts, said means being constructed and arranged to permit angular adjustments of the thigh section relative to said upper parts and to permanently secure the section and said parts together 35 in different relative angular positions and hold them against relative movement during normal use of the leg.

2. In an artificial leg construction, a thigh section, a calf section, a pair of plate parts secured to the sides of said thigh section, a knee joint connecting said sections and comprising a pair of upper parts extending at the sides of the thigh section, each of the parts of one of said pair having a series of horizontally spaced openings therethrough, means connecting the parts at one side of the thigh in spaced relation to said openings, and means passing through a selected one of said openings in the parts at each side of the thigh section and securing the parts at the 50 respective sides of the thigh together with the thigh section in the desired angular relation to the calf section.

3. In an artificial leg construction, a thigh section, a calf section, a pair of plate parts secured to the sides of said thigh section, a knee joint connecting said sections and comprising a pair of upper parts extending at the sides of the thigh section, each of the parts of one of said pair having a series of vertically spaced openings therethrough, each of the parts of the other pair having a series of laterally spaced openings, and means passing through selected ones of said openings in the parts at each side of the thigh section and securing the parts at the respective sides of 55 70 75

the thigh section together with the thigh section in the desired position of vertical and angular adjustments relative to the calf section.

4. In an artificial leg construction, a thigh section, a calf section, a knee joint connecting said sections and comprising a pair of upper parts extending at the sides of said thigh section, and means connecting the thigh section to said upper parts for vertical and angular adjustments relative thereto, said means comprising members secured to the thigh section, a plurality of means connecting said members to the said upper parts at vertically spaced points and adapted to permit relative vertical adjustment between them, one of said securing means being constructed to permit relative pivotal movement between the said members and said parts, and the others of said connecting means being of a construction to permit relative lateral adjustment between the said members and said parts to adjust the thigh member about said pivots, whereby the thigh section may be secured to said upper parts in the desired position of vertical and angular relation to the calf section.
5. In an artificial leg construction, a thigh section, a calf section, a knee joint connecting said sections with their adjacent ends in spaced relation, a transversely curved knee cap plate secured to one of said sections and having a free end extending into the other section and slidably relative thereto at the fronts of said sections, and said plate comprising a flexible spring metal member adapted to flex as the knee joint is flexed and having its free end portion held against the latter section by the resiliency of the plate to close the space between the sections as the joint flexes.
6. In an artificial leg construction, a thigh section, a calf section, a knee joint connecting said sections, a lock comprising a means connected with one of said sections and having bearing engagement against the other thereof to limit flex-

ing of said knee joint, said means including relatively movable members and resilient yieldable means normally retaining said members in a given relative position but to yield a limited amount under pressure, means to move said first means out of such bearing engagement to permit flexing of the knee joint for bending of said joint when a wearer sits, and a spring to snap said first means back into such bearing engagement on straightening of the leg.

7. In an artificial leg construction, a thigh section, a calf section, a knee joint connecting said sections, a lock comprising a member pivoted at its upper end to said thigh section, a cylinder into which said member extends, a spring in said cylinder and resisting movement of the member into the cylinder, a bracket in said calf section and on which the lower end of said cylinder rests when the lock is in normal position limiting flexing of the knee joint, means to draw the cylinder off the bracket by swinging the member about its pivot to permit flexing of the knee joint when a wearer sits, and a spring to snap said cylinder back into position with its lower end bearing against said bracket on straightening of the leg.

8. In an artificial leg construction, a thigh section, a calf section, a knee joint connecting said sections, a lock comprising a means connected with one of said sections and having bearing engagement against the other thereof to limit flexing of said knee joint, means to move said means out of such bearing engagement to permit greater flexing of the knee joint, a spring to shift said first means back into such bearing engagement on straightening of the leg, and a manually shiftable catch carried by one of said sections and movable to a position to engage the lock means when out of bearing engagement for retaining said latter means out of such bearing engagement.

NICHOLAS MALLOY-BREHUNOFF.
